Primary Examiner — Maria J. Edwards

(57) **CLAIM**

The ornamental design for a stand for heat transfer printer, substantially as shown and described.

DESCRIPTION

FIG. 1 is a top, front and right side perspective view of a stand for heat transfer printer, showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.
